186,949

CLOCK OR SIMILAR ARTICLE

Theodore G. Daher, Stratford, Conn., assignor to General
Electric Company, a corporation of New York

Application July 27, 1959, Serial No. 56,943

Term of patent 14 years

(Cl. D42—7)

Fig. 1 is a front perspective view of a clock embodying my new design;

Fig. 2 is a front elevational view of the clock shown in Fig. 1; and

Fig. 3 is a bottom plan view of the clock shown in Fig. 1.

I claim:

The ornamental design for a clock or similar article, substantially as shown.
